SPORTSWEAR

Stanford Alexander, New York, N. Y., assignor to
Saqui & Co., Inc., a corporation of New York

Application October 6, 1937, Serial No. 167,498

2 Claims.

(Cl. 2—77)

This invention relates to improvements in sportswear and has for a principal object the provision of garments particularly suitable for outdoor wear, comprising combinations of upper and lower portions of garments, such as shirts, blouses, or bodices with trousers, slacks, culottes, riding pants, shorts, skirts, divided skirts, gymnasium suits, and bathing suits. The upper portions of such garments have portions permanently attached together, and other portions detachably secured to each other and include novel means for varying the length around the waist.

The novel construction to be hereinafter shown and illustrated makes it possible for people of different waist-lines who wear the same size garment, to adjust the waist-line of the garment and thereby secure a perfect fit.

A further object of the invention is the provision of an outdoor garment in which the upper portion or member and the lower portion or member are permanently secured together, with a belt therebetween, along an outline extending from the front center to the right side of the garment and across the back to the left side, a portion of the belt near one end being permanently secured to the lower portion of the garment from the front center to the left side, and the other end of the belt being free and carrying means adapted to be adjustably secured to a binding strip carried on the lower end of the upper garment and extending from the front center to the left side, adapted to be overlapped by the end of said belt permanently secured to the said lower garment.

Other objects will be obvious to those skilled in the art.

Referring to the drawing:

Figure 1 is a front view of one embodiment of the invention as applied to a pair of rompers, showing the panties-portion partially opened;

Figure 2 is an enlarged view of a portion of Figure 1, showing details of the improved adjustable feature;

Figure 3 is a view taken along the line 3—3 of Figure 2 showing the combination of the waist-line and the binding strip secured together for one length of waist-line;

Figure 4 is similar to Figure 3, but adjusted for a smaller waist-line;

Figure 5 is a fragmentary view of a garment similar to Figure 1, but provided with still another means for adjusting the length of the waist-line;

Figure 6 is a fragmentary view of a garment, such as that shown in Figure 1, but provided with

another type of means for adjusting the waist-line;

Figure 7 is a fragmentary view taken along the line 7—7 of Figure 6; and

Figure 8 is a view similar to and differing from Figure 2 as to details of the means for adjusting the length of the waist-line.

Referring now to Figure 1, the shirt member 10 of the garment is permanently secured to the panty-member of the garment 11 in certain portions by means of a belt generally designated by the numeral 12. The belt 12 has a portion 13 permanently secured to the shirt 10 from the front center 14 to the right side 15 and across the back of the garment to the left side 16. The belt 15 also has a portion 17 which is secured to the panty-member of the garment from the front center 14 to the left side 18. The belt also has a free portion 19 which is secured to neither the shirt nor the panty-member of the garment. The portion 19 carries a button 20 secured to one face thereof, and a button 21 secured to the opposite face thereof.

The portion of the shirt 10 between the front center 14 and the left side 16 is finished off with a suitable binding strip or wide reinforced hem 22, which carries buttons to presently be described. A space 24 is provided between the end 29 of the binding strip 22 and the point 16, so that the portion 19 of the belt may be made to underlie the binding strip 22; the button-hole 25 is buttoned to the button 20, thereby adjusting the garment for a short waist-line. The details of this may be seen in Figure 4, and when the garment is buttoned up, the button-hole 26 is 35 also buttoned to the button 20 and the button-holes 27 are buttoned on to the buttons 23. Thereafter the matching buttons and the button-holes up the front center and down the left leg are buttoned, and the wearer is completely dressed. 40

In cases where it is desired to adjust the garment for a long waist-line, the portion 19 of the belt would partially overlie the binding strip 22 and the button 21 would be buttoned into the button-hole 25 (extending in toward the wearer's body), as clearly shown in Figure 3, thus leaving the button 20 available to the button-hole 28 and the rest of the garment may be buttoned up in the manner described.

In the modification shown in Figure 5, the shirt portion 10* is provided with a binding strip 22* which may carry the male member 30 of a snap. The portion 19* of the belt may carry a plurality of female members 31, any one of which may engage the member 30 in accordance with the girth 50

of the wearer. The portion 18^a of the belt may also carry a button 28^a to which the button-hole 26^a, in the other end 17 of the belt, may be secured.

5 In the modifications shown in Figures 6 and 7, the binding strip 27^b carried on the shirt portion 18^b between the front center and the left side may have secured thereto a tab 32 carrying eyelets 33. The free portion 19^b of the belt is also 10 provided with a series of eyelets 34 and a lace 35 is provided to adjustably secure the portion of the belt 19^b to the tab 32, whereby the wearer may adjust the waist-line to any desired length.

15 After the desired adjustment is obtained, the button-hole 26^b may be buttoned on to the button 28^b, and the other buttons and button-holes may be combined in the manner hereinbefore described.

20 In the modification shown in Figure 8, the upper member 35 of the garment between the front center and the left side is provided with a binding strip 36 somewhat longer than the binding strip 22 shown in Figure 2. The belt portion 37 which is permanently secured to both the 25 upper member 35 and the lower member 38 from the front center to the right side and across the back and is not provided with a free end 19 such as shown in Figure 2, and instead terminates at the point 39 and is provided with a button 40 on 30 one face of the belt and a button 41 on the opposite face of the belt. The free end 42 of the reinforced binding strip 36 is adapted to overlie or underlie the end of the belt carrying said buttons in accordance with the final adjusted 35 length of the waist-line. The end 42 carries a button-hole 43, which may engage either the buttons 46 or 41. The garment is also provided, in addition to the regular buttons and button-holes, with elongated button-holes 44, 45, which engage 40 buttons 46, 47, respectively, and due to this elongation the buttons 46 and 47 take a normal position therein after the waist-line has been adjusted and the garment is buttoned up.

45 The new and improved garments made according to this invention not only give the wearer a comfortable and secure feeling, but also provide freedom of movement for the most strenuous of sports, and due to the adjustable feature the wearer is always neat and well dressed.

50 Although one embodiment and two modifications of my new and improved adjustable garment are herein described, it is obvious that many changes may be made from the modifications shown without departing from the spirit of the 55 invention and the following claims.

What is claimed is:

1. A combination garment for sportswear comprising a shirtwaist member having short sleeves and a shorts member, said shirtwaist member being formed to open in front from the neck downward to the center of the waistline of the garment, and the shorts member being formed to open along the left side from the waistline downward, a belt permanently secured to both said shirtwaist and said shorts from a point at the front center to the right side of the garment and across the back to and having a terminus at the left side of the garment, said belt also having a portion extending from the front center to the left side secured only to the shorts, a reinforced binding strip secured to said shirtwaist and extending from the front center to the left side of the garment, a button-hole formed in said reinforced binding strip near the left side of the garment, a button carried on the inside face of said terminus of the belt and a button spaced apart from said first button and carried on the outside face of said terminus of the belt, said button-hole being adapted to engage one of said buttons for obtaining one waist length and adapted to engage the other of said buttons for obtaining a different waist length.

2. A combination garment for sportswear comprising a shirtwaist member having short sleeves and a shorts member, said shirtwaist member being formed to open in front from the neck downward to the center of the waistline of the garment, and the shorts member being formed to open along the left side from the waistline downward, a belt permanently secured to both said shirtwaist and said shorts from a point at the front center to the right side of the garment and across the back to the left side of the garment, said belt also having a portion extending from the front center to the left side secured only to the shorts, and an end portion freely extending from the left side of the garment, a reinforced binding strip secured to said shirtwaist and extending from the front center to the left side of the garment, a button-hole formed in said reinforced binding strip near the left side of the garment, a button carried on the inside face of said free end of the belt and a button spaced apart from said first button and carried on the outside face of said free end of the belt, said button-hole being adapted to engage one of said buttons for obtaining one waist length and adapted to engage the other of said buttons for obtaining a different waist length.
